1,638,613

UNITED STATES PATENT OFFICE.

BEN CLIFFORD BLACKMON, OF DALLAS, TEXAS.

SUPPORT FOR COLLAPSIBLE CONTAINER TUBES.

Application filed April 13, 1926. Serial No. 101,714.

The present invention relates to improvements in supports for collapsible container tubes, and has reference more particularly to an improvement over the device covered 5 in Patent #1,568,868, granted to me on January 5, 1926.

One of the important objects of the present invention is to provide means adapted for cooperation with the neck or discharge 10 end of a collapsible paste tube whereby the tube will be held in position in the holder against accidental displacement therefrom.

Another important object of the invention is to provide a substantially concaved 15 closure cap which is adapted for disposition over the discharge end or mouth of the tube for preventing any possibility of the contents of the tube being wasted.

A further object is to provide a key which 20 has its intermediate portion slotted to receive the closed end of the tube, and around which the tube is to be wound or rolled as the contents are discharged from the tube, a handle being formed on each end of the 25 key so as to permit the same to be actuated from either the left or right side of the holder.

A further object is to provide a device of 30 the above mentioned character wherein the holder is provided with means for supporting tooth brushes thereon, thus providing a compact device which may be readily and easily attached to any suitable support, and will not occupy any considerable amount of 35 space.

A still further object is to provide a device of the above mentioned character which is simple in construction, inexpensive, strong, and durable, and further well adapted 40 to the purpose for which it is designed.

Other objects and advantages of the invention will become apparent during the course of the following description taken 45 in connection with the accompanying drawing.

In the accompanying drawing forming a part of this application and in which like numerals designate like parts throughout the several views:

1. Figure 1 is a front elevation of my improved device.

Figure 2 is a side elevation thereof.

Figure 3 is a bottom plan view, a part of the closure cap being broken away, and

5. Figure 4 is a detail sectional view through

the closure cap showing the same disposed over the mouth or discharge end of the tube, and also illustrating the locking cam or eccentric in engagement with the threaded neck of the tube.

In the drawing wherein for the purpose of illustration is shown the preferred embodiment of my invention, the numeral 1 designates generally the holder, the same being preferably formed from a single 60 blank of sheet metal material, the holder including the upturned side walls 2 and the bottom or end wall 3. The bottom or end wall 3 is provided with a centrally located substantially diamond shaped opening 4 through which is adapted to extend the threaded neck 5 of the collapsible tube 6, it being understood of course that the usual screw threaded cap provided for the threaded neck of the tube is initially removed.

The side walls 2 are provided with registering longitudinally extending slots such as are shown at 7 and through which is adapted to extend the key which is associated with the closed end of the collapsible tube for extruding the paste from the tube in the manner well known in the art. The specific construction of the key will be hereinafter more fully described.

An extension 8 is formed on the upper end of the holder, and the same is provided with an opening 9 for the reception of a nail or any other appropriate fastening means for securing the holder in a suspended position on any suitable support, preferably 85 a wall. The lower forward end of the holder is provided with supporting legs 10 which engage the wall and hold the lower end of the holder in spaced relation thereto in the manner as is clearly set forth in my prior Patent #1,568,868.

The upper ends of the side walls 2 are disposed laterally as at 11, and these lateral extensions are provided with the notches 12 to provide a means for supporting a tooth brush adjacent each side of the holder.

The key forming a part of the present invention is designated generally by the numeral 13 and the same is preferably formed of a single piece of wire, the intermediate portion of which is flattened as indicated at 14. The flattened portion is formed with a longitudinally extending slot 15 for the reception of the closed end of the paste tube 6, and it is of course understood that the 110

flattened portion 14 of the key is wound or rolled around the closed end of the tube in order to provide the necessary means for collapsing the tube in order to extrude the 5 paste from the mouth of the tube.

The ends of the wire key extend through the longitudinally arranged slots 7 in the respective sides 2, and each end of the wire is so bent as to form an actuating handle 16. 10 By forming a pair of handles on the respective ends of the wire key, the same may be actuated from either the left or right hand side of the holder.

The manner in which the key cooperates 15 with the closed end of the tube for dispensing the contents of the tube has already been more fully described in my prior patent, above referred to, and a thorough description thereof in the present application, is 20 therefore thought unnecessary.

An angular foot 17 extends laterally from the intermediate portion of the piece of metal from which the supporting legs 10 are formed, and pivotally secured at one end to 25 the angular foot as at 18 is a strip of metal 19. The outer free end of this strip has formed thereon a substantially concaved closure cap 20 which is adapted to be disposed over the mouth or discharge end of the 30 collapsible tube 6, in the manner as clearly shown in Figure 4 of the drawings, so that the contents of the tube is prevented from being accidentally discharged, thereby eliminating any waste. A depending lug or finger 21 is formed at the side of the strip 19 to provide a means whereby the pivoted closure cap may be swung into an operative or inoperative position. The strip of metal 35 19 and the closure cap associated therewith 40 are formed preferably of spring metal.

For the purpose of locking the collapsible tube in position in the holder against accidental displacement therefrom, I provide a locking cam or eccentric 22 which is pivotally supported on the bottom 3 as at 23, the 45 curved edge portion of the pivoted locking cam or eccentric being sharpened for cooperation with the threads formed in the neck of the paste tube in the manner as clearly 50 shown in Figure 4. This locking plate is also provided with a depending finger such as is shown at 24 at its outer free end where-

by the same may be readily and easily actuated.

The manner in which the pivoted locking 55 cam or eccentric cooperates with the threaded neck of the tube is clearly shown in Figures 3 and 4. A wedging action is obtained when the sharpened edge of the cam or eccentric is in engagement with the threaded 60 neck 5 so that the tube will be supported in proper position in the holder and it is obvious that when the finger 24 is actuated so that the pivoted cam or eccentric is moved out of engagement with the threaded neck, 65 the tube may be easily removed from the holder for the purpose of replacing an empty tube with a new one.

It will thus be seen from the foregoing 70 description, that I have provided a support for a collapsible tube which is very simple in construction, and may therefore be manufactured at a low cost.

The simplicity in which the various parts 75 of the device are arranged enables the same to be readily and easily actuated so that the pivoted closure cap may be swung away from the mouth of the tube in order that any desired quantity of paste may be discharged from the tube when the key is rotated by 80 turning either of the handles which extend from the respective sides of the holder.

While I have shown the preferred embodiment of my invention it is to be understood that minor changes in the size, shape, and 85 arrangement of parts may be resorted to without departing from the spirit of the invention and the scope of the appended claim.

Having thus described the invention, what I claim as new and desire to secure by 90 Letters Patent is:—

A paste tube holder of the class described including a bottom having an opening formed therein for receiving the threaded neck of a paste tube, and a non-yielding 95 member pivotally mounted on the bottom and having an arcuate edge eccentrically disposed in relation to the pivot for forming a cam edge for biting engagement with the neck so that the same may be held against 100 accidental displacement.

In testimony whereof I affix my signature.

BEN CLIFFORD BLACKMON.
